UNITED STATES PATENT OFFICE.

JEROME TRAVIS, OF CLINTON, MICHIGAN, ASSIGNOR OF ONE-HALF TO
BRADLY G. SWIFT, OF SAME PLACE.

BLACKBOARD-ERASER.

SPECIFICATION forming part of Letters Patent No. 365,356, dated June 21, 1887.

Application filed April 30, 1887. Serial No. 236,696. (No model.)

To all whom it may concern:

Be it known that I, JEROME TRAVIS, a citizen of the United States, residing at Clinton, in the county of Lenawee and State of Michigan, have invented certain new and useful Improvements in Blackboard-Erasers; and I do hereby declare the following to be a full, clear, and exact description of the invention, such as will enable others skilled in the art to which it appertains to make and use the same, reference being had to the accompanying drawings, which form part of this specification.

My invention relates to that class of devices commonly known as "blackboard-erasers," and has for its object to provide an eraser with a strip of erasing material that can be so adjusted and turned when any particular portion of it becomes worn out as to bring a fresh supply into use, and thereby enable the eraser to be used until all the erasing material is exhausted, when a new strip can be substituted, and the device made to operate as well as when new; and it consists in the construction hereinafter described, and more particularly 25 pointed out in the claims.

Heretofore in the construction of blackboard-erasers it has been common to permanently secure the erasing material to a block by means of glue or other adhesive material, or to so secure the material on the block by other means in such a way that it cannot be changed from its original position. In all of these constructions it is a well-known fact that the erasing material wears off at the ends and 35 sides of the erasers first, while in many instances that in the middle or body of the eraser remains good and could be used for a much longer time. Should the eraser be used after it is thus worn, its hard ends scratch through 40 the paint or enamel of the board without effecting the purpose for which it was intended, and in a short time the board becomes so damaged or worn from improper use as to render a new finish upon it necessary, or its substitution by a new board imperative. It has been 45 found impracticable to re-cover these worn erasers, from the fact that, in order to make them durable until the erasing material is worn out, even at the ends, the material has to be so rigidly secured to the block that the block is injured, or in many cases destroyed,

in the effort to remove the old material for the substitution of the new.

Referring to the drawings, Figure 1 is a perspective view of my invention ready for use. 55 Fig. 2 is a cross-sectional view on the line *x x* of Fig. 1. Fig. 3 is a perspective view with the erasing strip and clamp-band removed. Fig. 4 is a perspective view showing the erasing-strip on the block with the clamp band removed, and Fig. 5 is a view of the clamping-band removed.

Like letters of reference refer to corresponding parts in each figure of the drawings.

A represents a block of wood or other suitable material, which may be round, oval, oblong, or of any other desirable shape adapted for the use. The block is cut out at its base *a* to form a central portion, B, which is extended at some distance below the base to 60 serve as a holder for the erasing material. The base of the block is flared outward and upward at *b* to form a hand-hold for grasping it with when in use.

On the under side of the central portion, B, 75 there is one or more sheets of felt or other suitable erasing-pads, C, secured by means of glue or other adhesive material. These pads are made somewhat smaller in diameter than the surface of the extended portion B, and are 80 well filled with medium-sized holes or perforations *c*, to enable a deposit of chalk-dust around and within them during any continuous use upon the blackboard without removing the eraser therefrom.

Around the extended portion B there is placed a thick broad adjustable strip, D, composed of felt or other soft suitable erasing material, that extends from the flange *a* of the base to below the end of the extended portion, 90 terminating on the same plane with the lower surface of the pad C, leaving a space, *d*, for a dust-chamber between the strip D and the edge of the pad below the part B.

On the outer side and around the soft erasing-strip D there is a clamping-band, E, of sheet metal, of less width than the erasing-band. This band has formed at each end and projecting at right angles therewith an ear, F, of about the same width as the band, which 95 ears extend outward from one side or end of the block on a parallel line with each other,

and have screw-holes through them for the insertion of a screw, *f*, therein, for adjusting the band in holding the strip.

The lower edge of the band *E* has notches *c* 5 in its sides about midway its length, and that portion of the edge of the band between the notches is turned inward to form a flange or hold against the side of the erasing-strip to prevent the strip and band from slipping on each other after the band is adjusted thereon.

In operation, when the end or side portions of the erasing-strip *D* have become worn so that the wear is upon the ends or sides of the pad *C*, the screw *f* is turned partially out and 15 the band loosened sufficiently to enable the strip to be drawn down to provide additional wearing-surface at the ends. When worn at the ends, after being drawn down once or more, the screw is taken out, the adjusting-band *E* 20 is removed, and the worn portions of the erasing-strip are turned around to the sides of the holder and a portion of the sides brought to the ends, where, after being worn in like manner as in the first instance, it may in turn be 25 moved around, bringing a fresh unworn portion of the strip upon the ends or part receiving the greatest wear, until the strip is entirely consumed, except so much of it as is necessary to form a hold under the adjusting- 30 band. When the block is made round on its under side, instead of oval or oblong, the erasing-strip wears alike on all sides, and the band *E* only requires to be loosened and the strip drawn down from time to time, as it becomes 35 worn, until the erasing material is exhausted, when its place can be supplied with a new strip.

Should the pad *C* become worn and thin after long and continuous use, it being only on 40 the center of the block, it may be scaled off without serious injury to the block and a new

pad substituted therefor. Thus it will be seen that by my construction a blackboard-eraser is formed that may be used continuously for almost any length of time by occasionally supplying a new adjustable erasing-strip. 45

Having thus fully described my invention, what I claim as new, and desire to secure by Letters Patent of the United States, is—

1. The combination, with a blackboard-eraser 50 having a reduced extended portion provided with an erasing-pad on its under side, of an adjustable erasing-strip around the extended portion, as and for the purpose set forth.

2. The combination, with a blackboard-eraser 55 having an extended portion provided with a perforated erasing-pad smaller in diameter than the end thereof, of an erasing-strip adjustably secured around the extended portion, with its lower edge on substantially the same 60 plane with the under surface of the pad, as and for the purpose set forth.

3. The combination, with a block for a blackboard-eraser having a reduced extended portion provided with an adjustable erasing- 65 strip around it extending below the under side thereof, of an adjusting clamp-band around said strip over the reduced portion of the block, as and for the purpose set forth.

4. The combination, with a blackboard eras- 70 ing-block having an adjustable erasing-strip around it, of a clamping-band provided with holding-flanges on its edge and ears at its ends for an adjusting-screw, as and for the purpose set forth.

In testimony whereof I affix my signature in 75 presence of two witnesses.

JEROME TRAVIS.
